UNITED STATES PATENT OFFICE.

MAX PRICE, OF NEW EAGLE, PENNSYLVANIA.

ANTIREFILLABLE BOTTLE.

1,068,007.

Specification of Letters Patent.

Patented July 22, 1913.

Application filed November 6, 1912. Serial No. 729,900.

To all whom it may concern:

- Be it known that I, MAX PRICE, a citizen of the United States of America, residing at New Eagle, in the county of Washington and State of Pennsylvania, have invented certain new and useful Improvements in Antirefillable Bottles, of which the following is a specification, reference being had therein to the accompanying drawing.
- 10 This invention relates to anti-refillable bottles, and my invention aims to eliminate the nefarious practice of unscrupulous merchants in refilling bottles or receptacles that once contained a popular brand with an inferior grade and dispensing the same as the original article. This practice is prevalent in a great many trades and very often bottles that once contained a poison are used for other purposes resulting in the loss of life.
- 15 My invention further aims to provide a simple, durable and inexpensive bottle that cannot be completely emptied without disfiguring the bottle to that extent that the disfiguration will be noticeable and apparent
- 20 to a person using the bottle.
- 25 My invention will be hereinafter specifically described and then claimed and reference will now be had to the drawing, wherein:

- 30 Figure 1 is a side elevation of a bottle in accordance with this invention, Fig. 2 is a similar view partly broken away and partly in section, and Fig. 3 is a horizontal sectional view of the bottle.
- 35 An anti-refillable bottle in accordance with this invention comprises a receptacle 1 having a breast 2 provided with a neck 3. Formed integral with the upper end of the neck 3 is a closure 4 and adjacent to said closure the neck 3 has an annular exterior groove 5 that permits of the neck being easily broken to remove the closure 4. The removal of the closure 4 disfigures the bottle to that extent that it can be easily detected.

Formed integral with the breast 2 of the 45 bottle is a curved tube 6 that extends into the receptacle and has the inner end thereof closed, as at 7, and the sides of the tube provided with openings 8. The outer end of the tube protrudes from the breast of the 50 bottle and has a seat 9 for a stopper 10.

In practice the stopper is removed when the bottle is to be filled, and is also removed when a portion of the contents of the bottle is to be obtained; it being only possible to 55 obtain about two-thirds of the contents thereof through the tube 6. When it is desired to obtain the entire contents of a bottle the closure 4 is broken off from the neck 3 and contents discharged.

60 The bottle illustrated has been cited just as an example of one kind of receptacle that can be constructed in accordance with this invention, and I would have it understood that the invention is susceptible to such 65 changes as fall within the scope of the appended claim.

What I claim is:—

An anti-refillable bottle comprising a body portion having a closed bottom, a neck integral with said body portion and provided with an integral imperforate closure whereby the neck is sealed, an inwardly extending depending curved tube formed integral in proximity to its outer end with 70 the breast of said body portion and having a closed inner end and an open outer end, said tube in proximity to said closed inner end formed with side openings, and a stopper detachably mounted in the outer end of 75 80 said tube.

In testimony whereof I affix my signature in the presence of two witnesses.

MAX PRICE.
